AUTOMATIC FEED FOR HOOK FASTENERS

Leo Roseman, Newark, N. J.

Application June 19, 1930. Serial No. 462,249

16 Claims. (Cl. 112—196)

This invention relates to mechanism for automatically feeding hook fasteners and similar articles subject to various operations, such as attaching the same by sewing, stapling, riveting or other fastening operations, to garments or garment parts, hook and eye tape bodies, display cards, etc.

This invention has for its principal object to provide a simple and effective automatic hook feeding and delivery mechanism, whereby hook fasteners deposited in a holder or magazine are successively ejected therefrom and delivered in readiness for various operations to which it is desired to subject the same.

Other objects of this invention, not at this time more particularly enumerated, will be clearly understood from the following detailed description of the same.

Illustrative embodiments of this invention are shown in the accompanying drawings, in which:—

Fig. 1 is a side elevation of one form of hook feeding and delivery mechanism made according to this invention; Fig. 2 is a horizontal sectional view of the same, taken on line 2—2 in said Fig. 1; Fig. 3 is a fragmentary vertical section of the same, taken on line 3—3 in Fig. 2; Fig. 4 is a front elevation of the same, viewed in the direction of the arrow *x* in Fig. 3; Figs. 5 and 6 are views similar to that of Fig. 3, but respectively showing stages of the operation of the mechanism in the delivery of the hook devices; Figs. 7 and 9 are fragmentary sectional views showing additional operations of the mechanism when completing the delivery of the hook devices; and Fig. 8 is a fragmentary detail plan view of the hook push-plate as operatively related to a hook device.

Fig. 10 is a vertical sectional view of a modified form of the novel hook feeding and delivery mechanism; and Fig. 11 is a horizontal section of the same, taken on line 11—11 in said Fig. 10.

Fig. 12 is a vertical sectional view of another modified form of hook feeding and delivery mechanism within the principles of this invention.

Similar characters of reference are employed in the above described views, to indicate corresponding parts.

Referring to the drawings, the reference character 15 indicates the base on which the novel hook feeding and delivery mechanism is mounted. Suitably fixed on said base 15, as by screws 16 or any other desired fastening means, is guide block 17. Said guide block 17 is provided with a forward extension 18 preferably of reduced height. Formed in the extension 18, at the juncture thereof with the main body of the guide block 17, is a

drop-well 19. Formed in the upper side or top of said guide block 17 is a longitudinally extending guide or slideway 20 in which is reciprocably slidable a carrier member 21. Any suitable means may be provided for imparting properly timed reciprocable movement to said carrier member 21, as, e. g. the pivoted bell-crank lever 22, which may be actuated from any suitable source of power transmission including a suitable timing means (not shown). Formed in the forward end portion of said carrier member 21 is a hook receiving pocket 23, which extends vertically from top to bottom of said carrier member. Said hook receiving pocket 23 is of a length transversely of the carrier member, slightly exceeding the width of the base portion *a* of hook devices to be handled by the mechanism, and is of a width, longitudinally of the carrier member, slightly exceeding the thickness of said base portion *a* of said hook devices. Extending forwardly from said receiving pocket 23 is a vertical slot 24 of dimensions suitable to accommodate and provide clearance of the bill portion *b* of said hook devices.

Fixed on said guide block 17 to rise upwardly therefrom, and so that its lower end bridges across the carrier member 21, is a magazine 25, having a vertical channel 26 to receive the base portions *a* of hook devices deposited therein, and a channel 27 of reduced width adjoining the same to receive the bill portions *b* of said hook devices. A cover or back plate 28 is secured to the channeled face of said magazine 25 to close the rear side of the hook passage provided by said channels 26 and 27. The hook devices are deposited within the hook passage thus provided by the magazine so as to form a vertical column thereof arranged end to end, preferably overlapping as shown in the drawings, and subject to gravitation toward the bottom of the magazine and the carrier member 21. In order to definitely limit the stroke of the carrier member 21, and to assure the proper alignment of the receiving pocket 23 thereof with the hook passage of the magazine when the carrier member is retracted, it is preferable to provide shoulders 29 and 30 in connection with the carrier member. Removably affixed to the magazine is a stop member 31, which is engageable by the shoulder 29 when the carrier member is retracted, and is engageable by the shoulder 30 when the carrier member is advanced. Should it be desired to remove or disassemble the carrier member at any time, the stop member 31 may be loosened and withdrawn from the path of movement thereof, whereupon the carrier member may be withdrawn

from the slideway of the guide block.

- While I have shown and described the carrier member as capable of reciprocable movement, this is for the purpose of illustration only, since the specific form and movement of the carrier member is subject to a wide range of variation within the broad aspects of my invention, the only limitation essential being that a receiving pocket of the carrier member be movable thereby into and out of hook receiving alignment with the magazine.
- 10 Formed in the underside of said guide block is a slideway 32 in which a push-plate is reciprocably movable. Said slideway 32 extends forwardly beneath and across the drop well 19 and through the underside of the extension 18, to the outer extremity of the latter. Any suitable means may be provided for imparting properly timed movement to said push-plate 33 through the actuating lever 34 which engages the rear end thereof.
- 15 Said push-plate 33 is provided at its forward end with shoulders 35 to engage the base portion *a* of a hook device deposited in front thereof, and rearwardly of said shoulders 35 the push-plate is indented by a clearance notch 36 to receive the bill portion *b* of the deposited hook device. At one side, at least, the push-plate 33 is provided with a forwardly projecting finger 37 having a chamfered free end which extends beyond the forward limits of the base portion *a* of a hook device 20 operatively engaged by the push-plate. This finger 37 may be omitted, but is desirable when the hook feeding and delivering mechanism is used to insert the hook devices beneath a flap of a garment, holding tape body or the like, for similar purposes. In such cases, the finger 37 enters beneath the flap in advance of the hook device and raises the same sufficiently to assure the free unobstructed passage or movement of the hook device beneath such flap.
- 25 30 35 40 Formed in the vertical wall of the guide block 17 which bounds the rear side of the drop-well 19 is a vertical groove or channel 38 to provide clearance for the hook bill *b* when a hook device is initially manipulated by the push-plate 33 in the manner subsequently explained. In like manner formed in the under side of the extension 18 above the push-plate slideway is a longitudinal groove or channel 39 of dimensions calculated to provide clearance or passage for the hook bill *b* of a hook device propelled outwardly by the push-plate. Formed in the inner end portion of the extension 18 which borders the forward side of the drop-well 19 is an indented notch or slot 40 to pass the bill portion *b* of a hook device entered in said drop-well, and the under-marginal portion of said extension bordering said drop-well is downwardly and inwardly curved at the juncture of said drop-well with the push-plate slideway, as indicated at 41, thus permitting clearance for the base portion *a* of a hook device, as the same is turned from vertical standing position within said drop-well to a horizontal position within said push-plate slideway.
- 45 50 55 60 65 70 75 It is desirable to provide means to overlap garment or tape material, or cards or other material to and upon which the hook devices are to be delivered, so as to assure smooth unobstructed movement of the latter upon the former. To this end I provide intermediate the base 15 and extension 18 a resilient yieldable tongue 42 which normally lies within the end of the push-plate slideway 32, and in the path of a hook device advanced by the push-plate 33. The material upon which the hook devices are to be delivered may be moved beneath said tongue 42 so as to be over-

lapped by the latter. When a hook device is advanced by the push-plate said tongue 42 will yield to the passage thereof but, since the tongue overlies the material, the hook device will be guided over the edge of the material by the tongue, and will consequently ride smoothly and surely off of the tongue and on to the material. The tongue may be mounted in the described operative relation in many different ways. A convenient method of mounting the same however consists in forming the tongue 42 in connection with a shim plate 43 interposed and secured between the base 15 and guide block 17, as shown in the drawings.

In the operation of the form of hook feeding and delivering mechanism above described, when the carrier member 21 is retracted, its hook receiving pocket 23 is brought into alignment with the lower end of the magazine 25, whereby the lowermost hook contained in the latter will at once drop down into said receiving pocket (see Fig. 3). After a hook device is thus deposited in the receiving pocket of said carrier member, the latter is advanced, whereby the body of the carrier member closes the bottom of the magazine against hook discharge and whereby the receiving pocket is moved forwardly into alignment with the drop-well 19, so that the hook device may drop out of the receiving pocket and into the drop-well 19, in front of the push-plate 33, so that the hook device 105 is deposited with the lower end of its base portion *a* lodged within the push plate slideway 32 in advance of the shoulders 35 with which the forward end of said push-plate is provided (see Fig. 5). After the hook device is thus 110 disposed, forward movement is imparted to the push-plate, whereby the shoulders 35 engage the downward edge of the hook base *a* so as to push the same forward, thus causing the hook device to be turned into down lying position 115 with its bill rearwardly extending (see Fig. 6). Upon such occurrence, the push-plate 33 is partially retracted to allow the hook device to lie flat in the push-plate slideway, with its base *a* in front of the shoulders 35 (see Fig. 7). 120 When the hook device is thus disposed, a final forward movement is imparted to the push-plate 33, whereby the clearance notch receives the hook bill portion *b*, and the shoulders 35 engage the hook base portion *a*, so as to propel 125 the hook forwardly and outwardly through the slideway (see Figs. 8 and 9). As the hook device is thus propelled outwardly, the same is caused to ride over the tongue 42 and thence on to the material to which the same is to be 130 delivered. If the material happens to be a tape body *t* having a flap *t'* or the like beneath which it is desired to insert the hook base *a*, then the outwardly moving push-plate will carry the finger 37 beneath the flap *t'* in advance of the approaching hook, so as to lift said flap for ready and unobstructed admission of the hook base *a* thereunder (also see Figs. 8 and 9).

While the push-plate 33 is advancing to perform its functions, the carrier member 21 may 140 be retracted in position to receive within its receiving pocket 23 the next hook device to be delivered by the mechanism, and by properly timed relative reciprocations of said carrier member and push-plate, the above operations may 145 be successively repeated as desired.

Referring now to Figs. 10 and 11, I have shown therein a modified arrangement of the novel hook feeding and delivering mechanism, which is substantially the same as already above de- 150

scribed, except that the carrier member is disposed for transverse reciprocation relative to the magazine 25 and block 17 instead of for longitudinal reciprocation. In these views the modified carrier member is indicated by the reference character 21', and the same is provided with a receiving pocket 23' having a horizontal cross sectional shape corresponding to that of the channeled hook passage of the magazine. 5 In other respects the structure is the same as above described, as is witnessed by the application of corresponding reference characters to the details thereof.

Referring to Fig. 12, I have shown another modified form of hook feeding and delivering mechanism which is within the general principles of my invention. In this arrangement I provide a carrier member 44 disposed for reciprocable movement relative to the lower end 10 of a magazine 45. Formed in the under side of said carrier member 44 is a longitudinal slideway 46 in which a push-plate 47 is reciprocably movable directly against the under side of said carrier member. Provided in the carrier member, rearwardly of its forward free end, 15 is a receiving pocket 48, having a vertical clearance channel 49 in its rearward wall and a clearance notch 50 in its forward wall to accommodate movement of the bill portion *b* of a hook device deposited therein and moved relative thereto when upsetting the same from initial vertical to final horizontal position. Extending outwardly from said receiving pocket 48 to the free end of the carrier member, and 20 above and in communication with the slideway 46, is a channel or passage 51 for the hook bill *b* of a hook device moved outwardly by the operation of the push-plate 47. The juncture of said notch 50 and channel or passage 51 is 25 rounded off, as at 52, to provide clearance for hook movement when subject to upsetting operations. The forward end of the push-plate 47 is shaped to operatively engage the hook device in the same way as set forth with respect to the first above described form and arrangement embodying my present invention.

In the operation of this modified form of hook feeding and delivering mechanism, the carrier member 44 is initially retracted to align 30 its receiving pocket 48 with the hook passage of the magazine 45, whereupon a hook device will drop from the latter into the former. After a hook device is thus deposited in the carrier member, the latter is slid forward until the hook device is carried forwardly beyond the operative end of the retracted push-plate 47, whereupon the lower edge of the hook base portion *a* will drop down in front of said push-plate. After the hook device is thus positioned, an initial forward movement is imparted to the 35 push-plate 47, whereby the hook device is upset, following which the push-plate is partially retracted to permit the hook device to lodge flatly in front of the same, whereupon a final advancing movement of the push-plate will move the hook device beneath the forward end portion of the carrier member 44, so as to finally eject the hook device and deliver the same upon the material to which it is desired to relate the 40 same.

From the above description, it will be obvious that the instant invention is of simple and yet efficient character; that hook devices arranged to move in a train under gravity to form a supply, may be successively removed from such sup-

ply, properly positioned, and then finally delivered in such proper position to the point where desired operations with respect thereto may be carried on. The hook devices are at all times under control, and yet such freedom of movement thereof is afforded as to avoid jamming or stoppages, and consequently a smoothly functioning arrangement is assured.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

I claim:

1. In mechanism of the kind described, the combination with a magazine adapted to contain an upstanding column of garment hooks vertically aligned with their hook portions upward, of a carrier member movable across the bottom end of said magazine to engage a single hook and remove the same from said magazine, a pushing member, said carrier member on its operative stroke being adapted to deliver the removed hook in upright position to said pushing member, and said pushing member being operative to turn to flat lying position and then deliver said hook to the place of use.

2. In mechanism of the kind described, a magazine adapted to contain a column of garment hooks vertically aligned with their hook portions upward and subject to successive gravitational discharge therefrom, a movable carrier member having a hook receiving pocket movable relative to the discharge end of said magazine, and pusher means in a plane beneath that of said carrier member, said carrier member on its operative stroke being adapted to deliver a hook in operative relation to said pusher means, and said pusher means being adapted by its operative movements to dispose said hook in flat lying position and then deliver the same to a desired place of use.

3. In mechanism of the kind described, a magazine adapted to contain a column of garment hooks vertically aligned with their hook portions upward and subject to successive gravitational discharge therefrom, a guide block beneath said magazine, a carrier member slidably supported by said guide-block for movement across the discharge end of said magazine, said carrier member having a hook receiving pocket extending vertically therethrough, said guide-block having a drop-well formed therein beyond said magazine and beneath said carrier member, a pusher means, a slideway for said pusher means in the lower portion of said guide block extending across the lower end of said drop-well and to the forward end of said guide block, said slideway also forming a delivery passage for hook devices, and said guide block having clearance spaces formed therein to communicate with said drop-well and slideway to accommodate the bill portions of hooks manipulated by said pusher means.

4. In mechanism of the kind described, a magazine to contain a supply of hook devices in upright vertically aligned relation with their hook portions upward and subject to successive gravitational discharge therefrom, a guide block beneath said magazine, a reciprocable carrier member slidably supported by said guide block for movement across the discharge end of said magazine, said carrier member having a hook receiv-

- ing pocket extending vertically therethrough to hold a hook device upright therein, a reciprocable push-plate in a plane beneath that of said carrier member, a slideway extending through the lower portion of said guide block to accommodate said push-plate and to form a delivery passage for hook-devices, and said guide block being further provided with a drop-well beneath said carrier member and extending into said slideway, whereby upright hook devices advanced by said carrier member may drop into said slideway subject to operation of said push-plate whereby said hook devices are upset from upright to flat lying position and then ejected from said slideway to the place of use by a direct rectilinear movement. 80
5. In mechanism of the kind described, a magazine to contain a supply of hook devices in upright vertically aligned relation with their hook portions upward and subject to successive gravitational discharge therefrom, a guide block beneath said magazine, a reciprocable carrier member slidably supported by said guide block for movement across the discharge end of said magazine, said carrier member having a hook receiving pocket extending vertically therethrough to hold a hook device upright therein, a reciprocable push-plate in a plane beneath that of said carrier member, a slideway extending through the lower portion of said guide block to accommodate said push-plate and to form a delivery passage for hook-devices, said guide block being further provided with a drop-well beneath said carrier member and extending into said slideway, whereby upright hook devices advanced by said carrier member may drop into said slideway subject to operation of said push-plate whereby said hook devices are upset from upright to flat lying position and then ejected from said slideway to the place of use, and said guide block having clearance spaces formed therein to communicate with said drop well and slideway to accommodate the bill portions of hooks manipulated by said push plate by a direct rectilinear movement. 90
6. In a hook feeding and delivering mechanism, a movable carrier member to successively remove hooks in upstanding position from a source of supply, and a push-plate into operative relation to which said upstanding hook devices are delivered by said carrier member, said push-plate operating to turn said hooks to flat lying position and thereupon deliver the same to a desired place of use. 100
7. In a hook device feeding and delivering mechanism, a movable carrier member to successively remove hook devices in upstanding position from a source of supply, a reciprocable push-plate into operative relation to which said upstanding hook devices are delivered by said carrier member, and channeled means cooperative with said carrier member and push-plate for guiding the hook devices when manipulated thereby, said push-plate operating to turn said hooks to flat lying position and thereupon deliver the same to a desired place of use. 110
8. In hook device feeding and delivering mechanism, a movable carrier member to successively remove hook devices from a source of supply, a reciprocable push-plate in a plane beneath said carrier member, a guide block having a slideway for said push-plate, said slideway also forming a delivery passage for hook devices, and said guide block also having guide means between said carrier member and slideway to control the movement of hook devices discharged from said carrier member to said slideway for manipulation by said push-plate, said push-plate operating to position and deliver said hook devices through said slideway to a desired place of use. 120
9. In a hook device feeding and delivering mechanism, a movable carrier member to successively remove hook devices from a source of supply, a reciprocable push-plate in a plane beneath said carrier member, a guide block having a slideway for said push-plate, said slideway also forming a delivery passage for hook devices, said guide block also having guide means between said carrier member and slideway to control the movement of hook devices discharged from said carrier member to said slideway for manipulation by said push-plate, said push-plate operating to position and deliver said hook devices through said slideway to a desired place of use, and resilient means at the discharge end of said slideway beneath which material desired to receive delivered hook devices may be positioned and over which said hook devices are delivered on to said material. 130
10. In mechanism of the kind described, a magazine to contain a supply of hook devices in upright positions and subject to successive gravitational discharge therefrom, a guide block beneath said magazine, a carrier member slidably supported by said guide block for movement across the discharge end of said magazine, said carrier member having a hook receiving pocket extending vertically therethrough to hold a hook device upright therein, a reciprocable push-plate in a plane beneath that of said carrier member, a slideway extending through the lower portion of said guide block to accommodate said push-plate and to form a delivery passage for hook-devices, said guide block being further provided with a drop-well beneath said carrier member and extending into said slideway, whereby upright hook devices advanced by said carrier member may drop into said slideway subject to operation of said push-plate whereby said hook devices are upset from upright to flat lying position and then ejected from said slideway to the place of use, said guide block having clearance spaces formed therein to communicate with said drop well and slideway to accommodate the bill portions of hooks manipulated by said push-plate, and resilient means at the discharge end of said slideway beneath which material desired to receive delivered hook devices may be positioned and over which said hook devices are delivered on to said material. 140
11. In a hook device feeding and delivering mechanism, a movable carrier member having a hook receiving pocket extending vertically therethrough, said carrier member being adapted to successively remove hook devices from a source of supply, and a reciprocable push-plate into operative relation to which said hook devices are delivered by said carrier member, the free end of said push-plate being shaped to receive the bill projecting from the hook base, said push-plate operating to position and deliver said hook devices to a desired place of use. 150
12. In a garment hook feeding mechanism, the combination with a downwardly open magazine adapted to hold a supply of hooks vertically aligned in upstanding positions, of a carrier member movable across the lower open end of said magazine, said carrier member having a hook receiving pocket to receive upstanding hooks singly from said magazine so as to hold 145

the received hook in substantially a vertical plane, movement of said carrier member operating to both carry the received hook away from the magazine and to temporarily close the magazine by its interposed body so as to obstruct downward discharging movement of the hook supply.

13. In a garment hook feeding mechanism, the combination with a magazine adapted to contain a supply of hooks vertically aligned in up-
10 standing positions and subject to gravitational discharge therefrom, a carrier member having a vertically open receiving pocket alignable with the discharge end of said magazine to receive up-
15 standing hooks singly from the latter, movement of said carrier member operating to close said magazine against hook discharge and to convey the received hook to a position where it may drop out of said pocket.

14. In mechanism of the kind described, a
20 push-plate having a rearwardly indented notch in its free end portion adapted to receive the hook end of a hook device, and having thrust shoulders extending transversely relative to op-

posite sides of said notch adapted to engage the base of said hook device, a finger at one side of said push-plate forwardly extending from the line of said thrust shoulders, said finger having a chamfered free end to lift material for entrance thereunder of the base of a hook device advanced by said push-plate.

15. In mechanism of the kind described, a carrier means to receive garment hook devices in upstanding position, and a pusher member, said carrier means being adapted to deliver an upstanding hook device in front of said pusher member, and said pusher member being adapted to turn the hook device to flat lying position and then deliver the same to the place of use.

16. In combination with means to insert a hook device with its base engaged beneath a flap of material to which the hook device is to be attached, of a means for lifting said flap preparatory to the movement of the hook base thereunder.
